METHOD OF MAKING PLASTER GROUNDS

Walter S. Edge, Atlanta, Ga.

Application November 15, 1938, Serial No. 240,477

8 Claims. (Cl. 140—3)

My invention relates to a method of producing reinforcement mesh that is particularly adapted for use in the building of walls, ceilings, and floors, etc., where reinforcement is desired for a body or slab of plaster, concrete or stucco material, or the like.

The invention is especially applicable to that class of structures wherein a wire mesh reinforcement is employed for plastic material such as plaster, concrete, etc., and is backed by a form sheet of paper, wire cloth, burlap or other more or less flexible material, the composite mesh and sheet being frequently designated as "plaster ground" or "plaster base."

One object of my invention is to provide a method of producing a plaster base of unusual rigidity to enable it to be easily handled and nailed or otherwise fastened in place.

Another object is to provide a method which results in a plaster ground of unusual stiffness after erection so that it will withstand the action of the plasterer's trowel and avoid the use of an excessive amount of plaster.

Another object of my invention is to provide a method whereby a plaster ground is produced of such form that the plaster body formed thereon will be of greater strength, relative to its thickness and weight, as compared to forms of structures heretofore employed.

Another object is to provide a method which is particularly suitable for producing a structure of such rigidity that it will enable the product to be used in floor construction where it must support considerable vertical loads of wet concrete or mortar before the same has set.

It will be understood that it is imperative that a plaster base of the type herein described should have sufficient stiffness to enable it to be handled easily before and during erection. Also it must be stiff enough and resilient enough to withstand the pressure due to the plasterer's trowel or the weight of the wet suspended plaster, if it is used on a ceiling, or the downward pressure due to men walking on it or the weight of wet concrete, if it is used in floor construction.

In the accompanying drawings, Figure 1 is a face view of a wire fabric and a backing sheet therefor; Fig. 2 is an enlarged view taken on the line II—II of Fig. 1; Fig. 3 is an enlarged view taken on the line III—III of Fig. 1; Fig. 4 is a view taken on the line IV—IV of Fig. 2; Fig. 5 is a view similar to Fig. 2, but showing the stucco or plaster applied thereto; Fig. 6 is a sectional view of another form of light structural rib which may be employed, and Figs. 7, 8 and 9 show other

forms of ribs which may be used for the same purpose. Fig. 10 is a face view of a plaster ground similar to Fig. 1, except that a different type of stiffening rib is employed and the lacing wires which hold the backing sheet against the rear of the fabric sheet run parallel to the ribs instead of across them as they do in Fig. 1; Fig. 11 is an enlarged section on line XI—XI of Fig. 10, and Fig. 12 is an enlarged section on line XII—XII of Fig. 10.

Referring first to Figs. 1 to 5, the structure includes a sheet of fabric having stay wires 18 and 15 to which are welded marginal strand wires 14 and light structural ribs 13 of V cross section. The wires used in the welded structure are preferably of low carbon content (.12½ carbon or less), in order to secure better welds than is possible with high carbon wire. Stay wires 18 and 15 are preferably hard drawn to give the resulting fabric greater rigidity and resiliency.

A backing or form sheet 17 is supported against the rear side of the fabric, by lacing wires 16 which should be of hard drawn wire to provide a resilient support for the backing sheet which will yield slightly under the pressure of plastering but will prevent the use of an excessive amount of mortar. The backing sheet 17, for interior plaster work, should preferably be one having a rough fibrous surface and possessing as high a wet strength as possible. For stucco work it should be a water resistant paper such as an asphalt treated kraft paper.

The lacing wires 16 lie mainly behind the backing sheet, as shown in Fig. 1, but are threaded therethrough at intervals where they overlie and are supported by the light structural ribs 13. Lacing wires 16 may or may not be welded to the ribs 13, depending upon the method used in manufacture.

The ribs 13 are preferably flattened at either end where they are welded to the marginal stay wires 18 to reduce the thickness of the plaster ground at these points. This is necessary to reduce the thickness of two overlapping sheets at vertical joints which will ordinarily be directly in front of studding to which the plaster ground is attached.

Where one method of manufacture is used, the backing sheet 17 is brought in contact with the rear side of the welded structure composed of stay wires 18 and 15, strand wires 14 and ribs 13 which are welded together, and lacing wires 16 are inserted by first deflecting outwardly those portions of the backing sheet 17 between the ribs 13, and then inserting the lacing wires as the

backing sheet and mesh are advanced by suitable feeding means.

Another method of manufacture will enable the entire assembly to be made on one machine.

- 5 Here the backing sheet 17, the stay wires 18 and 15, and the lacing wires 16 will be fed through the machine, the wires 18 and 15 being on top of the sheet and the lacing wires 16 being underneath the sheet. As the sheet passes through the machine, narrow slots 16A will be punched in 10 the backing sheet at points corresponding to the visible parts of lacing wires 16, in Fig. 1. Then the backing sheet will be pressed down at these points, allowing the lacing wires 16 to come 15 through the slots 16A, and then the ribs 13 will be fed in from the side under wires 18 and 15, and under the visible portions of the lacing wires 16, but above the backing sheet, and thus serve also as retaining members for the wires 16. 20 The entire assembly of wires 18, 15 and 16 may then be welded to the ribs 13 and marginal wires 14, or the stay wires 18 and 15 only may be so welded, the resulting plaster ground being practically the same as was obtained by the first 25 method.

A third method of manufacture would be to first assemble the backing sheet 17, the lacing wires 16 and the ribs 13, and to then weld the rib members 13 to the mesh wires 15 and 18.

- 30 When the plaster ground has been secured to studding or other supporting members, the plaster 19 (Fig. 5) is applied in the usual manner, the backing sheet 17 being held by the lacing wires 16, against the rear side of the ribs 13 and 35 intermediate portions of the stay wires 15, with sufficient force to prevent excessive deflection of the backing sheet under plastering pressure.

- In applying the plaster the backing sheet will be pushed slightly away from wires 15 and ribs 13, 40 but it will be sprung back by the lacing wires 16, so that there will be complete embedment of the wires 15 and ribs 13, without excessive thickness of plaster and with consequent saving in plaster and reduction in weight and cost of the 45 structure.

- Referring now to Figs. 6, 7, 8 and 9, I show several forms which the rib may take instead of the one shown in Figs. 1 to 5. In Fig. 6, 21 is a light Z section to which stay wire 20 is attached. In 50 Fig. 7, a channel section 23 is used and in Fig. 8 an angle 25 fulfills the same purpose. In Fig. 9 a V section 27 similar to the one shown in Figs. 1 to 5 is shown, but instead of the stay wire 26 being welded across the top of it, it is welded 55 across the bottom. These various light structural sections are employed to give the structure rigidity. They must be light in order to be cheap and easily cut with hand shears in the hands of the workman.

- 60 In Fig. 10 I show a slightly different form of plaster ground in which the stay wires 28, 29 and 29a consist of straight parallel wires as in Figs. 1 to 5, but they are welded to light structural ribs 30 of channel form in cross section. 65 The ends of these members 30, where they are welded to marginal stay wires 28 in Fig. 10, are flattened to provide a thinner structure at the lap as was previously explained. The backing sheet 33 is deformed in much the same manner 70 as in the previous design, but the lacing wires 32 extend parallel to the ribs and are supported by the stay wires 29a. The lacing wires should be of hard drawn wire so that they are resilient and will provide an elastic support for the 75 backing sheet. In order to get the best results with

this agreement it is frequently necessary to support the lacing wires 32 only on alternate or every third stay wire, instead of every stay wire. By doing so a more resilient support for the backing sheet and better coverage of the wires 29 5 and ribs 30 is obtained. This design also eliminates the need for crimping the lacing wires, and, as in the case of the lacing wires 16, no permanent or "set" bends need be formed there- 10 in.

It will be understood that sheet material other than paper will sometimes be employed. For example, very fine woven wire screening or loosely woven textile materials, such as burlap, could be used.

15 The structure of Fig. 10 may be assembled in somewhat the same manner as that of Fig. 1, in that the lacing wires 32, the preliminarily-slitted sheet 33 and the mesh, may be placed in superposed relation and the sheet and the lacing wires 20 relatively deflected at the slits, to permit insertion of the retaining wires or bars between the sheet and the lacing wires, at the slits; thus the wires 29a will initially be free of the mesh, so that when the sheet 33 and the lacing wires are relatively deflected at the slits, these wires 29a can be slid into position between the forwardly deflected portions of the lacing wires 32 and the sheet, and can thereafter be welded to the members 30 and 31.

25 It will be noted that rib elements 21, 23, 25 and 30 have their web portions extending perpendicularly to the plane of the mesh and their outer edges flanged in parallelism with the plane of the mesh wires. The rib elements are of course 35 embedded by the plaster and said flanges serve to anchor the plaster to these ribs, and the perpendicular webs provide maximum stiffness for a given amount of metal.

30 I claim as my invention:

1. The method of making plaster ground which comprises forming rows of transversely aligned slits in a backing sheet, positioning lacing wires at the rear side of the sheet and a mesh at the front of the sheet, deflecting the sheet 45 and the lacing wires relative to one another, so that portions of the lacing wires will extend forwardly through the slits, inserting retaining members between the sheet and the said forwardly-extending portions of the lacing wires, in 50 a direction crosswise of said wires, and connecting the retaining members to the mesh.

2. The method of making plaster ground which comprises forming rows of transversely aligned slits in a backing sheet, positioning lacing wires 55 at the rear side of the sheet and a mesh at the front of the sheet, deflecting the sheet and the lacing wires relative to one another, so that portions of the lacing wires will extend forwardly through the slits and the mesh, and inserting 60 retaining members between the face of the mesh and the said forwardly-extending portions of the lacing wires, in a direction crosswise of said wires.

3. The method of making plaster ground which 65 comprises forming rows of transversely aligned slits in a backing sheet, positioning lacing wires at the rear side of the sheet and a mesh at the front of the sheet, deflecting the sheet and the lacing wires relative to one another, so that portions of the lacing wires will extend forwardly 70 through the slits, inserting retaining members between the sheet and the said forwardly-extending portions of the lacing wires, and behind the mesh, in a direction crosswise of said wires, 75

and welding the retaining members to the mesh.

4. The method of making plaster ground which comprises positioning lacing wires at the rear side of a sheet, deflecting the sheet and the lacing wires relative to one another, so that portions of the lacing wires will extend forwardly through the sheet, inserting reinforcement members between the sheet and the said forwardly-projecting portions, in a direction crosswise of the lacing wires, and connecting the reinforcement members to a mesh.

5. The method of making plaster ground which comprises positioning lacing wires at the rear side of a sheet, deflecting the sheet and the lacing wires relative to one another, so that portions of the lacing wires will extend forwardly through the sheet, inserting reinforcement members between the sheet and the said forwardly-projecting portions, in a direction crosswise of the lacing wires, and welding the reinforcement members to the rear side of a reinforcement mesh.

6. The method of making plaster ground which comprises positioning lacing wires at the rear side of a sheet, deflecting the sheet and the lacing wires relative to one another, so that portions of the lacing wires will extend forwardly through the sheet, and inserting reinforcement members between the sheet and the said forwardly-projecting portions, in a direction crosswise of the

lacing wires, the lacing wires being of resilient material and deflected through the sheet along lines of such small angularity relative to the plane of the sheet that permanently set bends will not be formed therein.

7. The method of making plaster ground which comprises positioning a series of lacing members against the rear side of a sheet, deflecting the sheet and said members relative to one another, so that portions of the lacing members will extend forwardly through the sheet, inserting a series of retaining members between the sheet and the said forwardly-projecting portions, in a direction crosswise of the lacing members, and connecting one of said series to reinforcement elements.

8. The method of making plaster ground which comprises forming rows of transversely aligned slits in a backing sheet, positioning lacing wires at the rear side of the sheet, opposite to said slits, positioning a mesh at the front of the sheet, deflecting the slit portions of the sheet to a plane rearwardly of the lacing wires, inserting retaining members between the wires and the said rearwardly portions of the sheet, in a direction crosswise of said wires, and connecting the retaining members to the mesh.

WALTER S. EDGE.
